COMBINED RULER, MEMO PAD HOLDER AND DESK SET

Michael Barron, Woodmere, N.Y.

Application March 6, 1959, Serial No. 54,867

Term of patent 14 years

(Cl. D74—1)

FIG.1

FIG.4

Figure 1 is a rear perspective view of a combined ruler, memo pad holder and desk set, showing my new design; the broken line illustration of a memo pad and pens being for illustrative purposes only;

I claim:

The ornamental design for a combined ruler, memo pad holder and desk set, substantially as shown and described.
